UNITED STATES PATENT OFFICE.

EDWARD E. KILBOURN, OF NEW BRUNSWICK, NEW JERSEY, ASSIGNOR TO THE
KILBOURN KNITTING MACHINE COMPANY.

CIRCULAR-KNITTING MACHINE.

1,018,063

Specification of Letters Patent.

Patented Feb. 20, 1912.

Application filed December 16, 1902. Serial No. 135,420.

To all whom it may concern:

Be it known that I, EDWARD E. KILBOURN, citizen of the United States, residing at New Brunswick, in the county of Middlesex and State of New Jersey, have invented certain new and useful Improvements in Circular-Knitting Machines; and I do hereby declare the following to be a full, clear, and exact description of the invention, such as will enable others skilled in the art to which it appertains to make and use the same.

My invention relates to the art of knitting seamless hosiery and more particularly to the class of circular knitting machines that are used in knitting seamless stockings and it consists in certain new constructions and combinations of parts whereby such machines are enabled to produce stockings possessing decided features of novelty and which such machines have been unable to produce prior to my invention.

In the accompanying drawings I have shown one form in which I have contemplated embodying my invention and such invention is disclosed in the following description and claims.

In the said drawings, Figure 1 is an elevation of the left hand end of a machine of the type described embodying my present invention. Fig. 1^a is a similar view of the right hand end of the machine, the two views forming an elevation of the front of the machine. Fig. 2 is a partial elevation of the rear side of the same machine, and Fig. 2^a is another partial view in elevation of the same side, the two views forming a complete elevation of the rear side of the said machine. Fig. 3 is an elevation of the left hand end of the machine. Fig. 4 is an elevation of the thread carriers and their supporting parts looking from the left hand end of the machine. Fig. 5 is a section on line x—x, Fig. 4, looking downward. Fig. 6 is an enlarged detail of the ends of the thread guide slides engaged by the cams for operating such guides. Fig. 7 is a detail in perspective of the parts for operating the thread guide cams. Fig. 8 is a partial view (in elevation) of the rim of the pattern wheel. Fig. 9 is a view of the interior of the upper cam cylinder developed in a straight line. Fig. 10 is a similar view of the stationary ring between the cam cylinder. Fig. 11 is a sectional view of said cam ring. Fig. 12 is a view of the interior

of the lower cam cylinder developed in like manner. Fig. 13 is a partial view of the upper cam cylinder. Fig. 14 is a sectional view of the upper cam cylinder on line y—y of Fig. 13. Fig. 15 is a partial plan view 60 of the lower cam cylinder. Fig. 16 is a section of the same on line 1—1 on Fig. 12. Fig. 17 is a view of the cam engaging slides or jacks forming a part of the needles of the upper cam cylinder. Fig. 18 is a view 65 of the like parts of the lower cam needles. Fig. 19 shows the manner of loosely connecting the two parts of the needles. Fig. 20 is a detail in perspective of the parts employed to control the movable cam of the 70 upper cam cylinder. Fig. 21 is a view of the periphery of the pattern cam wheel developed in a straight line. Fig. 22 is a partial view of the inside of the same. Fig. 23 is a detail view in perspective of the parts 75 for controlling the movable cam of the lower cam cylinder. Fig. 24 is an enlarged detail of the lever operated upon by the pattern wheel. Fig. 25 is a detail of shaft G and attachments. 80

In these drawings I have shown the novel features of my invention as applied to a circular knitting machine of the general type shown in my former Patents No. 669,730, Mar. 12, 1901, and No. 679,281 of 85 July 23, 1901. The machine shown in said patents is a full automatic machine for knitting full and half hose and is provided with mechanism for narrowing and widening to produce the heel and toe pockets and 90 these operations are brought about at the proper times by automatic appliances. Such mechanism is shown in the drawings as forming a part of the machine in which my improvements are embodied. 95

One of the new results accomplished by my improved constructions is the knitting of a lace stocking which is also striped, and said stripes extend across the lace portions as well as across the plain knitted portions. 100 Another of the results produced by my present machine is the varying of the pattern or lace work at different intervals down the leg of the stocking, if this is desired.

Another result accomplished is the forming of open work sections down the back of the leg of the stocking as well as on the front of the stocking and these open work sections are closed and plain knitting is resumed before the narrowing and widening 105 110

mechanism is put in operation. This open work upon the back is controlled by pattern mechanism and can be commenced and discontinued at any point or points desired 5 without in any manner affecting the lace work on the front of the stocking. I am also enabled to knit a different pattern upon the front and upon the back of the leg of the stocking if this be desired and can 10 change the work on the front and on the back independently of each other.

In the machine shown in the drawings A is the bed plate of the machine and A' A' 15 A' A' the supporting standards, these parts constituting the main supporting frame for the operating mechanism.

The machine is provided with two cam cylinders of like character to those of the earlier patents above referred to. Each cam 20 cylinder engages and operates one half of the needles of the machine. The cam cylinder C engages and operates the needles which knit the front half of the stocking and the cam cylinder B engages and operates the needles which knit the back half of the stocking and the heel and toe pockets. These cam cylinders are mounted and operated in substantially the same manner as the two cam cylinders of the patents above 25 referred to. The results set forth are accomplished mainly by the peculiar arrangement of cams in the cam cylinders and the mode of controlling and operating them.

In Fig. 9 I have shown the interior of the 30 upper cam cylinder B developed in a straight line. In this figure b is the usual knitting cam for ordinary plain knitting. b' is another cam of similar size and form except that it is of about half the thickness of cam b. This device although termed a cam, might be given another appellation and termed "switch," as it changes or switches the needles that are engaged by it from the position occupied by them when they are 35 unaffected by this device. The needles operated upon by this cam cylinder are shown in Fig. 17. In the Patent No. 679,281 above referred to the needles used in the machine are shown with the upper end provided with 40 the hook and latch rigidly secured to the main body of the needle which is of flat thin material to fit loosely in the needle grooves of the needle cylinder. In my improved machine I prefer to form each needle in two parts X and X'. The upper part being provided at its lower end with a short portion y at approximately right angles to the main body and each of the lower portions are provided with a notch v' on its inner side 45 to receive the same. When placed in the grooves of the needle cylinder the two parts of the needle work together in as effective a manner as if rigidly connected, while in 50 case the hook or latch become broken a new upper part is easily supplied.

The movements of the needles are caused and controlled by parts which engage the lower part X' of the needle, by reason of the construction of the same and as this construction is the only part which is modified or changed in the needles used by me in this instance, this lower part is the only portion of the needles shown in the drawings except in one instance in which the method of uniting the two parts is illustrated.

As it is of no importance in the operation of the machine whether the two parts of the needle are rigidly or loosely connected, we shall herein refer to the peculiarities of 60 construction by which results sought are obtained, as appertaining to needles, meaning to include thereby both forms of construction. The needles shown are provided with 65 nibs (X⁰, X⁰¹ and X²), for engaging the knitting cams. It will be seen that the nib X⁰¹ is of about double the length of nibs X⁰. The thread guide which is in operative position at any time delivers the thread to the needles the proper distance in advance of cam b to be caught by all of the needles and depressed to cast off the loop previously formed by the needle and form a new loop. On the further forward movement of the cam cylinder the needles provided with nibs x⁰ are unaffected by the cam b', the nibs x⁰ being of such length as to pass the cam without engaging it. Such needles, however, as are provided with the nibs x⁰¹ of greatest length, when the cam b' 100 is in the position shown in Fig. 9, are engaged by the cam b' and the needle is depressed casting off the loop on the needle. The tension on the web thereupon draws the loop out in a straight line forming an 105 open work space.

When the cam b' is depressed so that its ends enter the recesses shown in dotted lines, the nibs of all of the needles pass over this cam with the result that all of the needles of this cam cylinder knit plain stitches. Cam b' is firmly secured to the slide b², fitting in a groove in the cam cylinder and a pin (b³) passing through an aperture in the slide extends outwardly 110 through a slot in the cam cylinder and is secured to a lever B² pivoted to the outer side of the cam cylinder. This device might be termed the actuating member as it is the element of the mechanical combination that 115 actuates or moves the cam or switch to its different positions. The free end of this lever is provided with an outwardly extending projection b⁴ which is, at the proper times, engaged by a cam B³ pivotally secured to a standard mounted on the stationary ring interposed between the cam cylinders.

The free end of lever B² is rounded and is engaged by one of the inclines of the point- 120

ed end of the slide or sliding detent b^5 to hold it in either its elevated or depressed position. This sliding detent or retainer b^5 is movably mounted in a guide way b^6 on the outside of the cam cylinder and is yieldingly held in contact with the lever B^2 by the spring b^6 .

The cam B^3 engages the lever B^2 and by such engagement moves the lever or actuating member either upward or downward. This engaging member of the mechanical combination is preferably termed a cam and is operated to effect the necessary changes in the position of the cam b' by certain instrumentalities which I will now proceed to describe.

In the patents above referred to a cam wheel is used to control the work of the machine and to bring about the changes from circular work to reciprocating work in conjunction with the narrowing and widening devices and which latter devices are brought into and thrown out of operation by the said wheel. This cam wheel is retained in my present machine to perform the same functions and also to control the position of the cam b' through appropriate intervening mechanism. This cam wheel which is designated by the reference letter D is provided near the outer edge of its rim with pins c on the inner face of the rim. A bell crank lever d has an arm d' adapted to be engaged by these pins and thereby draw down link d^2 which is pivotally connected with the other arm of the lever d . A rock shaft D' extending across the machine and journaled in suitable bearings is provided with an arm d^2 to which the upper end of the link d^2 is connected.

At the rear of the machine (see Fig. 20) the opposite end of the rock shaft D' is provided with the arm d^4 , which arm extends to the right and beneath the rod D^2 . The rod D^2 is mounted in bearings so as to turn and slide freely in them. To the upper end of the rod D^2 is secured the arm E and said arm is provided with the pin e extending downwardly and when the rod D^2 is in its lower position this pin engages the periphery of the cam disk E' , which is secured to the upwardly extending portion of the vertical shaft B^8 , which drives the cam cylinders. Said shaft and cam disk are of substantially the construction shown in the Patent No. 669,730 hereinbefore referred to and which are therein designated by the reference letters A^8 and S .

Below the arm E an arm E^2 is loosely mounted on the rod D^2 . A pin e secured in the arm E engages an aperture in the arm E^2 so that the two arms move in unison laterally but the arm E will be permitted to rise with the rod, while the arm E^2 remains stationary. Between the arm E^2 and the upper bearing of the rod D^2 is the coiled spring

e^2 surrounding the rod D^2 one end of which is secured to the arm E^2 , and the opposite end to the upper bearing of the rod D^2 . This spring is so adjusted as to cause the pin e of the arm E to press against the periphery of the cam disk E' and to cause the arm to move toward the shaft upon which the cam disk is mounted when the pin is raised above the rim of the disk.

The arm E^2 is provided with a screw e^3 by which the amount of movement of the arms E and E^2 under the influence of the spring is regulated.

The outer end of the arm E^2 is depressed and provided with an opening therethrough in which is loosely mounted the rod E^3 . The opposite end of the rod E^3 is pivoted to the outer end of a crank b^6 on a rock shaft B^4 to which the cam B^3 is secured. The bearing of the rock shaft B^4 is provided at one side with two lateral extensions b^8 and b^7 and a pin b^{10} secured to the cam B^3 extends between them and the extent of the movement of the cam B^3 is thereby limited.

On one side of the arm E^2 the rod E^3 is provided with a cotter A^{3x} and on the opposite side a spiral spring is placed around the rod and held against the arm E^2 by another cotter e^4 . This arrangement provides for giving the full movement to the cam B^3 required without the necessity of securing a perfectly exact adjustment of the arm E^3 , as the movement in each direction is not rigid but effected by springs.

When a pin on the cam wheel D moves the lever d to turn the rock shaft D' , the arm d^4 is moved upward raising the rod D^2 and arm E and also raising the pin e above the cam disk E' , the spring e^2 then throws the arm E toward the center of the cam disk E' carrying the arm E^2 with it causing it to move the rod E^3 to turn the rock shaft B^4 so as to raise the point b^9 of cam B^3 . In such position the next revolution of the cam cylinder will bring the projection b^4 to engage with the underside of the cam B^3 and move the lever B^2 and the cam b' downward to their lower positions.

The cam disk E' has an upwardly extending rim. Inside of the rim a web e^5 extends from the rim to the hub of the disk. At one side of this web e^5 the rim of the disk is cut-away and the space fitted with a pivoted gate e^6 normally held closed by a spring e^7 . When the projections on the inside of the rim of the cam wheel D no longer hold the rod D^2 up, the rod drops and the pin e drops down within the rim of the cam disk E' . As the cam disk revolves the pin e comes in contact with the web e^5 which carries it outward. The gate e^6 yields to permit it to pass to the outside of the disk and then closes holding the pin and arms E and E^2 in the position seen in the drawing. This movement of the arms E and E^2 moves the

rod E³ to turn the rock shaft so as to throw the point of the cam B³ downward. When moved to this position on the next revolution the projection b⁴ on lever B² will engage the upper side of the cam B³ and thereby raise the lever B² and cam b' to their higher position.

The needles which engage and are operated by the lower cam cylinder are shown in Fig. 18. As will be seen these needles are provided with nibs of two different lengths z and z'.

In Fig. 12 I have shown the interior of the lower cam cylinder C developed in a straight line. In this figure c is the knitting cam or the cam for depressing the needles to cause them to cast off the loops held on them. This cam engages the nibs of all of the needles. After the needles pass the lowest point of this cam they are slightly raised to relax the tension on the thread. The nibs of the needles then rest on the ledge c' until they are reached by cams c², c³. The cam c² is formed with the upper part of the same of about one half the thickness of cam c forming the lower ledge c' above the plane of the ledge c' and below the upper ledge c⁵. The nibs of all of the needles operated by this cam cylinder are engaged by cam c² and raised as high as the ledge c⁴. At this point the needles divide those having the longer nibs continuing up along the incline of the cam to the ledge c³ by which movement the needles are raised so as to cause the loops on the needles to pass over the latches of the needles and into position to be cast off when the needles are again depressed by cam c. The other needles having the shorter nibs z pass along the ledge c' until they reach the cam c³. When the cam is in the position shown in Fig. 12 the needles with the short nibs z are raised and the loops thereon pass over the latches of the needles. The needles now again take the thread and on the cam c again engaging them a stitch is knit by each. The cam c³ is, however, movable and can be depressed to a position in which the upper face of the cam will be in the plane of the ledge c⁴. When in this position the needles are high enough to engage the thread but the latch not having passed above the loop on the needle, when such needles are depressed they will not cast off but still retain the loops on them and the threads subsequently caught or taken by the hooks of the needles. If now the cam c³ be raised the needles with the short nibs will be raised to pass the latches through the loops held upon them and taking another thread will be operated by the cam c to form a stitch, thus producing what is known as the tuck stitch. The cam c³ is secured by a screw passing through a slot in the cam cylinder to a slide C' which is movably mounted in a groove or guide

way on the outer side of the cam cylinder. The slide passing behind the toothed ring on the cam cylinder, said ring becomes a part of the guideway for the slide. This slide C' is provided with a short projection f. (See Fig. 15.)

The stationary ring F interposed between the upper and lower cam cylinders is provided on its inner side with a nearly continuous short inwardly projecting flange f'. When the cam c³ is in its higher position the projection f of the slide C' rests upon the flange f' and is securely held in the higher position.

When the cam is in the lower position the projection f of the slide C is below the flange f' and is kept thereby from moving out of position. At one point the flange f' is cut away and a pointed switch cam F' is pivoted in the space thus provided. The pivot of the cam extends to the outside of the ring and is then provided with the crank f² by means of which the free end of the cam is moved up or down to change the position of the slide C' and cam c³. This cam F' is actuated to move cam c³ to its higher and lower positions and to produce these intermittent stitches by means which I will now proceed to describe.

The cam wheel D hereinbefore referred to is provided with a gear wheel D^x rigidly connected with or forming a part of the same, and motion is imparted to the said cam wheel by a pinion on shaft G which gears with the gear wheel D^x. The shaft G extends transversely of the machine, is mounted in suitable bearings and projects slightly beyond the side opposite the cam wheel D. (See Figs. 3 and 25.)

Near the outer end of the shaft G is a ratchet wheel G' which is engaged by a pawl g actuated by a cam or eccentric G^x on a shaft, located transversely of the machine. On shaft G near the frame of the machine is placed a pattern cylinder H of less size than the cam wheel D which is provided with projections h. The connections between this pattern cylinder and the cam F' are as follows: A compound lever I composed of two parts i i' (see Fig. 23) is placed near the pattern cylinder H. The part i is pivoted to the frame of the machine and has a projection extending at an angle to the main body of the lever to engage the pins on the pattern cylinder. Near the free end of the part or lever i is pivoted the part or lever i'. The lower end of this lever i' has a lug or projection i² projecting from the side opposite the lever i. This lug or projection engages a notch in an arm j secured to a rock shaft J extending transversely of the machine. This rock shaft is provided with a spring j' which tends to turn the rock shaft in a direction to cause the arm j to bear upon the

projection of the lever i' and keep the projection in the notch of the arm thereby holding the lower end of the lever i' from movement. The other end of the rock shaft 5 J is provided with an arm j^2 , the outer end of which lies in the path of a projection on the cam wheel D. When the lever i is engaged by a pin of the pattern wheel, the free end of the same is raised upward and 10 when the lower end of the lever i' is held in the notch of the arm j the upper end of the lever i' is given a corresponding degree of movement. The upper end of the lever i' is notched or recessed to engage 15 the outer end of an arm k projecting from a vertical rock shaft K. The upper end of this rock shaft is provided with an arm k' which bears against an arm l depending from a second rock shaft L extending longitudinally of the machine. The opposite end of the rock shaft is surrounded by a spiral spring l' one end of which is secured to the rock shaft and the other end of which is secured to a bearing of the shaft in such 20 25 30 35 40 45 50 55 60 65 70 75 80 85 85 90 95 100 105 110 115 120 125 130 manner as to force the arm l against the arm k' of the rock shaft K. Adjacent to the spring l' the rock shaft L is provided with an upwardly extending arm l^2 , the upper end of which has an opening therethrough. Through this opening passes a rod L' , the opposite end of which is pivoted to the crank f^2 of the switch cam F'. A cotter l^3 is passed through the rod L' just outside of the arm l^2 and on the opposite side of the arm, the rod is encircled by a coiled spring l^4 which is held against the arm by another cotter l^5 . These connections are such that when the lever c is engaged by a pin of the pattern wheel, the crank f^2 is moved to turn the point of the pivoted switch cam F' up and on the projection f of the cam slide C' coming into engagement therewith the slide and cam c^3 are forced downward and the shorter nibbed needles are caused to take the thread without forming and casting off stitches. When the end of lever i leaves a pin of the pattern wheel the spring l' turns the rock shaft L and forces the end of the lever i' against the plain surface of the pattern wheel. It also moves the rod L' outward and turns the pivoted cam F' downward, thereby raising the slide C' and cam c^3 and causing the needles controlled thereby to knit until the cam is again forced to its lower position.

When the cam wheel D is turned to such a position that the arm j^2 is engaged by a riser or projection on the wheel and the arm moved to turn the rock shaft, the arm j on the opposite end of the rock shaft is raised and the projection on the lower end of the lever i' is released from the notch in the arm j . The lower end of the lever i' is then free to move and on the nose

or projection on the lever i coming in contact with a pin on the pattern wheel H, the lower end of the lever i' will be moved outwardly, without affecting the rock shafts K and L.

In order that stripes of different colors may be introduced into the web in the order and at the times desired, I provide the machine with the desired number of guides to carry threads of the colors selected for that purpose. In this instance I have shown three thread guides for supplying thread for the leg and foot of the stocking and a reciprocating thread guide for supplying a thread for reciprocating work, the latter being substantially that used for the same purpose in my former machine shown in Patent No. 669,730.

In the main the means for supporting the thread guides is substantially the same as that shown in said patent. M is, in this instance, the revoluble sleeve carrying the thread guides and the tube for conducting the threads to the said guides as in my said former patent. The construction of the thread guides and of their operating mechanism is shown in Fig. 4. In this figure M' indicates a sleeve revolvably mounted on the depending sleeve of the arm M extending above the needle cylinder as in my former Patent No. 669,730. This sleeve is provided with the horizontally extending plate m , which forms the upper guide plate for the thread carrier slides, and the plate m' forms lower guide plate. The slides n , n' , n^2 are of a form best seen in Fig. 5 having the main body composed of a rectangular frame, the opening within the same permitting the slides to be placed in position with the depending sleeve of the arm M' passing through such opening. The slides have at one end depending thread guides n^3 , n^4 , n^5 and at their opposite ends bearings to be engaged by the operating cams O, O' to move them in and out of operative position.

At one side of the needle cylinder and the mechanism immediately connected therewith is a standard M² with which the arm M is pivotally connected and from which the arm extends. In bearings connected to such support is a rod o^2 mounted so as to slide readily either up or down in a vertical direction. To the top of this rod is secured an arm o , extending toward the center of the needle cylinder, and this arm carries the cams O, O' which are located in two different horizontal planes. One of these cams engages the ends of the thread guide slides to force the thread guide outward across the circle of needles and the other engages them to force them in the opposite direction. The arrangement is such that when the cam I is in a position to move the bottom slide into operative position, the cam O' 130

- will so engage with the other two slides as to move them in the opposite direction and to maintain them in such position until the cams are moved to a different position.
- 5 The lower end of the rod o^2 is cam faced to be readily operated upon by means which I will now proceed to describe.
- The pattern wheel H is broad enough to have applied thereto another row of pins 10 h' . These pins are of as many different heights less one as there are thread guides. As there are in this instance three thread guides, the pins are of two different heights. To the frame adjacent to the pattern wheel 15 H is pivoted the lever P which has a downwardly extending projection p to engage the pins h' on the pattern wheel. To this lever is pivoted the lower end of a link p' . The upper end of this link is pivoted to an 20 arm q of rock shaft Q, which is mounted in suitable bearings and extends longitudinally of the frame. This rock shaft near its opposite end is encircled by a spring q' having one end secured to the rock shaft and 25 the other end secured to one of the bearings of the rod in such a manner as to force the lever P down upon the pattern wheel and move the rock shaft in opposition to the pins of the pattern wheel. Rigidly secured 30 to this rock shaft is the arm Q' , the upper end of which is provided with a segmental head having concentrically curved seats one less in number than the number of movable thread guides employed and arranged as 35 described. In this instance there are two such seats, q^2 and q^3 . The lower cam faced end of the rod o^2 which carries the cams O, O' is in line with and in the pathway of the segmental head of the arm Q' when 40 moved by the pins of the pattern wheel.
- When the lever P is not raised by any of the pins of the pattern wheel H, the rod o^2 and the cams O, O' are in their lowest position and the slide adapted to be thrown into 45 operative position by the cam O when in this position is so moved that its thread carrier or guide is outside of the circle of needles and in position to deliver thread thereto. When the lever P is raised by one 50 of the shorter pins of the pattern wheel the segmental head of the arm Q' is moved inward and the cam faced end of rod o^2 is engaged and raised to the seat q^2 in which position the cam O will move another 55 thread guide outward while the cam O' will retract the former slide and thread guide. When the lever P is raised by the higher of the two pins, the arm Q' will be further moved raising the rod to the seat q^3 and 60 bringing the cams O, O' to their highest position to throw outward the other thread guide.
- In order that the machine may be operated when so desired to knit continuously 65 with one thread, I provide the shaft Q^2

which is provided with the arm q^4 connected by the link q^7 to an arm q^8 of the shaft Q on the side of the shaft opposite the arm q . The shaft Q extends to the opposite side of the machine and is there provided with a downwardly extending arm q^9 . This arm is above a part of the periphery of the cam pattern wheel D and this wheel is provided with a riser q^4 to engage and move the arm q^8 , shaft Q², and turn the shaft Q² so as to raise the lever P out of contact with the pins of the wheel H. So long as the riser q^4 engages the arm q^8 the lever P will not engage the pins of wheel H and will not change the position of the thread guides, and the machine will knit with a single thread. As the wheel H moves a great deal faster than the wheel D which makes one revolution during the knitting of one complete stocking, I am thus enabled to make 85 color patterns in which there shall be portions of considerable width knit by one color and yet leave the wheel H arranged for a quicker change of colors in portions intermediate of this broader stripe. 90

In order that the thread guides may pass over the needles without engaging them, I provide the lower cam cylinder with the cam c^4 . The needles at the point of the cylinder where the guides pass are those 95 which are actuated by the upper cam cylinder, such needles of this cam cylinder as are required to be depressed are provided with the nib X² which engages the cam groove of the lower cylinder, and the upper cam cylinder has the supporting needle ledge b² provided with the depression b⁷ which permits these said needles to be depressed for the purpose stated. As the knitting cams of the two cylinders when revolving are in line 10 with each other vertically this arrangement does not cause one cam to interfere with the other, while as the upper cam is alone operated during the narrowing and widening operation the needles are not depressed at 11 this point during said operations of narrowing and widening.

The mode of operating the different parts of the machine has been herein described, but to more fully disclose the connected 11 operation of the whole of the parts in the course of knitting, an entire stocking, such operation is here set forth more in detail.

The machine shown is designed and arranged to knit a stocking having on the 12 back of the stocking leg rows of open work which are commonly known as "drop stitches," extending lengthwise and down to near the heel of the stocking. At the points in the needle cylinder at which it is desired 13 to have the open work spaces, needles to be operated by the upper cam cylinder having the longer nibs X² are placed in the needle cylinder.

The front of the stocking is to be orna- 14

mented by similar rows of drop stitches or a lace work pattern composed of drop stitches and tuck stitches at certain regular intervals. The drop stitch spaces are secured by 5 removing needles from the needle cylinder where these open spaces are desired and where the tuck stitches are required for the particular pattern the needles shown in Fig. 18 having the shorter nibs Z are inserted in 10 the needle cylinder.

So long as the arm d' of the lever d bears against the inner face of the rim of the cam wheel D the cam b' of the upper cam cylinder will be in its raised position and all of 15 the needles that are operated by said cylinder which have the longer nibs X' will cast off their loops forming open work spaces. When it is desired to change to solid plain knitting, pins are inserted upon the inner 20 face of the rim of said cam wheel in the row of apertures provided for that purpose. In the present instance I have inserted pins to change to plain knitting only just before beginning the heel of the stocking and con- 25 tinue the same until after the toe of the stocking is finished.

The upper part of the back of the leg may, however, be knit in solid plain knitting if preferred and the open work caused to begin 30 at a particular point thereafter, or the open work spaces may be knit in short sections upon the back of the leg, if preferred. In case plain knitting precedes the open work spaces the loops dropped by the needles 35 should be secured by a line of stitches by hand or by sewing machine or secured by crocheting.

After the needles operated by the lower cam cylinder have been put in place, pins h' 40 to control the cam c' so as to form the pattern desired are to be placed in the pattern wheel H. In the present instance I have shown three pins placed in the wheel, one following the other and the pins omitted 45 from a space equal to two pins. Three pins are then inserted and so on. This will cause the needles having the shorter nibs z to take the thread without casting off for three courses and to knit a stitch for each of the 50 next two courses.

When it is desired to have these shorter nibbed needles of the lower cam cylinder knit a stitch on each revolution of the cylinder, the cam wheel D is provided with 55 a projection to engage the arm j' of the rock shaft J. So long as this riser or projection holds the arm j of the rock shaft elevated so as to free the lever i' from the notch in said arm, the rock shafts K and L 60 will not be affected by the pins h of the pattern wheel and the needles of the lower cam cylinder will knit a plain web with open work spaces caused by the removed needles. The cam wheel D may be provided 65 with risers or projections at such intervals

as to form alternate bands of open work and tuck lace work across the front of the stocking.

It may sometimes be desired to ornament the front of the stocking by tuck stitches 70 without making open work spaces further than is produced by such operation. In such case none of the needles actuated by the lower cam cylinder are removed from the machine, but needles with the shorter nibs z are placed at the points where it is desired 75 to have the tuck stitches.

The pins h in the pattern cylinder are then arranged to produce the pattern of tuck knitting desired, and the cam wheel D 80 is provided with such risers or projections as will give the tuck knitting at such portion of the stocking as at that time is preferred. It will then be seen that the particular pattern will be knit when the cams of the lower cylinder are controlled by the pattern cylinder and that plain knitting will be produced when the lever I is rendered inoperative by risers on the cam wheel. By combining these mechanisms and their modes of operation in this manner, it is apparent that a large number of different ornamental effects 85 can be produced.

From the foregoing, it will be seen that the work of each cylinder can be controlled 90 independently of the other, and that the pattern knit on one half of a course of stitches may be different from the pattern of the other half, and that independent pattern mechanism is provided for the back and 95 front of the stocking.

When the machine has knit the web down to the heel of the stocking and circular work is discontinued, the depending thread guides for striping are turned to a position about 100 the center of the needles operated by the lower cam cylinder and remain in this position during narrowing and widening in the same manner as the thread guide for circular knitting is disposed during the same 110 period in my former Patent No. 669,730.

The cams O and O' are raised and lowered 115 while the machine is knitting the heel but as the ends of the striping thread guide slides are stationary and at another part of their path of movement, they are unaffected by them.

I do not desire to limit myself to the exact form of construction herein shown and described as many different forms of mechanism 120 may be employed to effect the results described without departing from the principle of my invention.

What I claim and desire to secure by Letters Patent is:—

1. In a circular knitting machine having independent needles, the combination with the stitch forming mechanism for making plain knitting, of mechanism for forming knitting of a different character, mechanism 130

for producing color stripes around the web, narrowing and widening devices, and means for arresting the rotary movement of the striping mechanism and holding the same 5 out of operation during the operation of the narrowing and widening devices, substantially as described.

2. In a circular knitting machine having independent needles, the combination with 10 the stitch forming mechanism for forming plain knitting, of mechanism for forming knitting of a different character, mechanism for producing color stripes around the web, narrowing and widening devices, means for 15 arresting the rotary movement of the striping mechanism and throwing the same out of operation before the narrowing and widening devices are put into action, substantially as described.
3. In a circular knitting machine, the combination with the needle cylinder, of independently movable needles, a cam mechanism for actuating said needles to knit, said needle cylinder and cam mechanism holding 25 said needles to right line reciprocatory movements, and automatic means for causing certain of said needles to drop their stitches and cease from knitting at a predetermined point.

4. In a circular knitting machine, the combination with a needle cylinder, of independently movable needles, cam mechanism for actuating said needles to knit, said needle cylinder and cam mechanism holding 30 said needles to right line reciprocatory movements, and means automatically causing certain needles to drop their stitches and cease from knitting at a predetermined point.

5. In a circular knitting machine having 40 independent needles, cam mechanism to cooperate with each needle to produce solid plain knitting, a further mechanism to cooperate with certain needles of a continuous portion of said series to cause them to drop 45 the loop carried by them and cease knitting, the said certain needles to be so controlled being provided with longer nibs than the other needles of the said continuous portion to which they belong.

6. In a circular knitting machine, having independent needles, cam mechanism to cooperate with all of said needles to produce solid plain knitting, a further cam mechanism to cooperate with certain needles of a continuous portion of said needles to cause 55 them to drop their stitches and cease from knitting, the said certain needles to be so controlled being provided with longer nibs than the other needles of said portion to which they belong.

7. In a circular knitting machine, the combination with a needle cylinder, of a series of independently movable needles, cam mechanism for actuating said needles to 65 cause them to knit, a part of said needles be-

ing provided with long and a part with short nibs to engage said cam mechanism, means for causing the needles with the longer nibs to drop their stitches and cease knitting, and means for causing said needles with the longer nibs to again knit, said means including a cam constructed to control the needles with the longer nibs for this purpose only, substantially as described.

8. In a circular knitting machine, the combination with a needle cylinder, of a series of independently movable cylinder needles formed into two sets, cam mechanism for actuating all of said needles to knit, a part of the needles of one set of needles 75 being provided with short and a part with longer nibs to be engaged by said cam mechanism, and means for engaging the longer nibbed needles to cause such needles to drop their stitches and to cease from knitting to 80 form open work, substantially as described.

9. In a circular knitting machine, the combination with the needle cylinder, a series of independently movable needles formed into two separate sets, separate cam 90 mechanism for engaging and operating the needles of each set, certain needles of one set being provided with longer nibs than the others of said set, and cam mechanism 95 cooperating with said longer nibbed needles to cause them to drop their stitches and cease to knit, certain needles of the other set being provided with shorter nibs than the others of the set and cam mechanism for cooperating with said shorter nibbed needles 100 of this set to cause them to knit stitches at certain predetermined intervals.

10. In a circular knitting machine having independent needles, the combination with the needle cylinder, needles and needle actuating devices, of mechanism for forming color stripes around the web, mechanism for causing certain needles to cease from knitting, narrowing and widening devices, means for calling the narrowing and widening devices into action, and means for stopping the rotary movement of the striping thread guides and throwing them out of operation before the narrowing and widening devices are put in operation.

11. In a circular knitting machine having independent needles, the combination with the needle cylinder, needles and needle actuating devices, of mechanism for forming color stripes around the web, mechanism for 11 causing certain needles to cease from knitting, narrowing and widening devices, means for putting the narrowing and widening devices into and out of action, and means for stopping the rotary movement of the striping thread guides and throwing them out of operation before the narrowing and widening mechanism is put into operation and means for putting the striping thread guides 12 into operation after the narrowing and 13

widening mechanism is thrown out of action.

12. In a circular knitting machine having independent needles, the combination with the needle cylinder, and needle actuating means, of narrowing and widening devices, means for striping the knitted web, means for causing certain of the needles to cease knitting whereby open spaces in the web are produced, means for bringing the narrowing and widening devices into operation and means for arresting the striping mechanism and for causing the needles not knitting to again knit before the narrowing and widening devices are called into action, substantially as described.

13. In a circular knitting machine, the combination with the needle cylinder, of independently movable needles, formed into two sets, one set for the front and one set for the back of a stocking, separate cam mechanism to actuate the needles of each set to cause them to knit, means for making one form of knitting by one set, means for making another form of knitting in the other set of needles, and means for changing the form of knitting of one set without affecting the knitting of the other set.

14. In a circular knitting machine, the combination with a needle cylinder and independently movable needles, of a cam cylinder for knitting the front part of a stocking, a separate cam cylinder for knitting the back of the stocking, means for knitting tuck stitches on the front of the stocking, means for knitting open work on the back of the stocking and means for changing the open work on the back of the stocking without affecting the knitting on the front of the same, substantially as described.

15. In a circular knitting machine having independent needles, the combination with the needle cylinder and needles, of means for knitting tuck stitches on the front of the stocking, means for knitting open work on the back of the stocking, striping devices, narrowing and widening mechanism, means for changing the open work on the back, and arresting the rotary movement of the striping devices and holding them out of operation during the operation of the narrowing and widening mechanism.

16. In a circular knitting machine having independent needles, the combination with knitting devices for forming plain stitches, on both front and back of the stocking, of mechanism for changing the character of the knitting on the front of the stocking, separate mechanism for changing the character of the knitting on the back of the stocking, and means for putting one of these mechanisms into and out of operation without affecting the other.

17. In a circular knitting machine having independent needles, the combination with

the devices for forming plain stitches around the web, of mechanism for forming ornamental stitches on the front of the stocking, a separate mechanism for forming ornamental stitches on the back of the stocking and means for changing the character of knitting on the front and back independently of each other.

18. In a circular knitting machine having independent needles, the combination with the knitting mechanism for forming plain stitch knitting around the web, means for changing said mechanism to form ornamental stitches around the web, mechanism for forming color stripes around the web, means for stopping the rotary movement of the striping mechanism and means for changing the knitting of different character to plain knitting at one part of the web, substantially as described.

19. In a circular knitting machine having independent needles, the combination with knitting mechanism for forming plain stitch knitting around the web, of narrowing and widening devices; mechanism for producing ornamental knitting on the front of a stocking, mechanism for producing ornamental knitting on the back of a stocking, mechanism for producing color stripes around the stocking, means for putting the narrowing and widening devices into operation and means for stopping the rotary movement of the striping mechanism, putting such mechanism out of operation, and means for changing the knitting on the back of the stocking to plain knitting before the narrowing and widening devices are put in operation.

20. In a circular knitting machine having independent needles, the combination with knitting devices for forming plain knitting around the web, of mechanism for forming ornamental knitting at one part of the web, an independent mechanism for forming ornamental knitting at another part of the web, and a separate pattern mechanism for each mechanism knitting ornamental stitches, whereby changes in one part of the web may be made without affecting the work in another part, substantially as described.

21. In a circular knitting machine, the combination with a needle cylinder, of a series of independent needles, cam mechanism moving around said needle cylinder to actuate the needles to form plain stitch knitting, mechanism to cause the machine to knit ornamental stitch knitting in one part of the course around the web, and another independent mechanism for causing it to knit ornamental stitches in another part of the same courses around the web.

22. In a circular knitting machine having independent needles, the combination with the needle cylinder, needles and actuating mechanism for forming plain stitch knitting, of mechanism for forming ornamental

mental knitting in one part of a course of stitches, another mechanism for forming ornamental knitting in another part of the same course, and means for causing one of the mechanisms for forming ornamental knitting to cease from operation while the other continues in operation.

23. In a circular knitting machine having independent needles, the combination with 10 the needle cylinder, of a cam cylinder for actuating a part of the needles of the machine, a cam cylinder for actuating another part of the needles of the machine and an independent mechanism for each cylinder 15 for forming ornamental knitting by the needles actuated by each.

24. In a circular knitting machine having independent needles, the combination with the knitting devices for forming plain 20 knitting, of mechanism for forming ornamental knitting in one part of a course of stitches around the web, another and independent mechanism for forming ornamental stitches of a different character in the 25 same course, and independent controlling means for each of said mechanisms.

25. In a circular knitting machine having independent needles, the combination with knitting devices for forming plain 30 stitches, of mechanism for forming ornamental knitting in one part of a course of stitches around the web, another and independent mechanism for forming open work in the same course and independent controlling means for each of these mechanisms, substantially as and for the purpose 35 set forth.

26. In a circular knitting machine having independent needles, the combination 40 with the knitting devices for forming plain knitting, of mechanism for forming ornamental stitches in one part around the web, another and independent mechanism for forming ornamental stitches of a different 45 character in another part of the web, a striping mechanism for supplying threads of different colors entirely around the web, means for controlling the striping mechanism and independent means for controlling 50 the character of knitting in different parts of the web.

27. In a circular knitting machine having independent needles, the combination with the needle cylinder, of two cam cylinders 55 for operating the needles of the needle cylinder, of a striping mechanism including thread guides that are made to pass from one side of the circles of needles to the other, one of said cylinders being provided 60 with a cam to depress the needles of the other cylinder at the point at which the thread guides cross the circle of needles.

28. In a circular knitting machine having independent needles of the class described, the combination with the knitting 65

mechanism, of mechanism for knitting ornamental knitting at one point around the stocking, an independent mechanism for knitting ornamental knitting at another point around the stocking, and independent controlling mechanism for each ornamental knitting mechanism.

29. In a circular knitting machine having independent needles, cam mechanism to coöperate with all of said needles to 70 produce circular work, means to coöperate with the knitting means and a continuous portion of the needles of the machine to produce narrowed and widened fabric, means to coöperate with certain needles of 75 said portion without causing them to knit, and a controlling means for throwing these mechanisms into and out of operation, substantially as described.

30. In a circular knitting machine having independent needles and means for narrowing and widening the back of the knit tube, means for knitting open work and plain knitting at any point around the knit tube, means for changing the work on the back of the tube to plain knitting and controlling mechanism for throwing said mechanisms into and out of operation separately, substantially as described.

31. In a circular knitting machine having independent needles, cam mechanism to coöperate with all of said needles, to produce tubular work, to coöperate with each needle of a continuous portion of said needles to form narrowed and widened fabric, and to operate certain needles of 95 said portion without causing them to knit, thereby forming open stitch work, and pattern mechanism to independently control the operation of the cam mechanism and co-operative means, substantially as described.

32. In a circular knitting machine having independent needles, cam mechanism to coöperate with a continuous portion of said needles to form narrowed and widened fabric, means to operate certain needles without causing them to knit, actuating means for said devices and variable pattern mechanism actuated from said actuating means to throw the cam mechanism and other means into and out of operation, substantially as described.

33. In a circular knitting machine having independent needles, the combination with the needle cylinder and needles of 100 mechanisms for forming ornamental knitting on the front of the leg of a stocking, separate mechanism for forming ornamental knitting on the back of a stocking, and means for changing the character of the 105 knitting on the front and back of the stocking independently of each other, substantially as described.

34. In a circular knitting machine having independent needles, the combination 110

- with the needle cylinder, of mechanism for knitting plain and ornamental knitting on the front of the stocking, separate means for forming plain and ornamental knitting 5 on the back of the stocking, and means for changing the character of the knitting in one part of a course of stitches without affecting the knitting in another part of the same course, substantially as described.
- 10 35. In a circular knitting machine having independent needles, the combination with the needle cylinder and needles of mechanism for knitting plain and ornamental knitting on the front of a stocking, separate mechanism for knitting plain and ornamental knitting 15 on the back of the stocking and means for controlling said knitting whereby the character of knitting can be changed on both back and front at the same time and the 20 character of the knitting can be changed on the back and front independently of each other.
36. In a circular knitting machine having independent needles, the combination with 25 the knitting mechanism, of narrowing and widening devices, mechanism for knitting open work, means for throwing the open work mechanism out of action, means for throwing the narrowing and widening devices into operation, and actuating means 30 for said knitting means, the said actuating means also actuating the open work and narrowing and widening devices, substantially as described.
- 35 37. In a circular knitting machine having independent needles, the combination with the needle cylinder and needles, of means for knitting plain and ornamental knitting on the front of the stocking, means for knitting plain and open stitch knitting on the 40 back of the stocking, narrowing and widening devices, means for controlling the ornamental knitting on the front of the stocking and independent means for causing the 45 needles on the back of the stocking to knit plain knitting before the narrowing and widening devices are called into action, substantially as described.
38. In a circular knitting machine, the 50 combination with the needle cylinder, of independently movable needles, cam mechanism to coöperate with all of said needles to produce circular work, said needle cylinder and cam mechanism holding said needles 55 to straight line reciprocating movements, means for actuating certain needles of a continuous part of the same less than the entire number of needles, at each revolution of the machine without causing them to knit, and 60 a controlling mechanism for said means for throwing the same into and out of operation, substantially as described.
39. In a circular knitting machine, the 65 combination with the needle cylinder, of independently movable needles, cam mecha-
- nism for operating the needles, narrowing and widening devices, means for causing certain needles at the back of a stocking to cease from knitting to form ornamental fabric, and means for causing them to knit 70 plain fabric, the said needle cylinder and operating cam mechanism holding said needles to straight line reciprocating movements and automatic controlling mechanism for the narrowing and widening devices and 75 the said needles at the back of the stocking.
40. In a circular knitting machine having independent needles, the combination with a needle cylinder and needles formed into 80 two sets, one for the front and one for the back of the stocking, separate cam mechanism for actuating each set of needles to knit, said cam mechanism and said needle cylinder holding said needles to right line reciprocating movements, means for making 85 plain and ornamental knitting on the front, means for making plain and ornamental knitting on the back, and means for changing knitting in one set without affecting the 90 knitting of the other set, substantially as described.
41. In a circular knitting machine having independent needles, the combination with a needle cylinder and needles formed into 95 two sets one for the front and one for the back of the stocking, separate cam mechanism for actuating the needles of said sets to knit, said cam mechanism and needle cylinder holding the said needles to right line 100 reciprocating movements, means for making plain and ornamental knitting by one set, means for making plain and ornamental knitting by the other set and means for changing knitting in one or both sets to 105 other than plain knitting, substantially as described.
42. In a circular knitting machine having independently needles, the combination with a plurality of knitting cams each adapted to 110 operate a series of needles to produce plain knitting in the knitted web, of additional cams for producing fancy stitches in the knitting and means for moving said additional cams into different positions while 115 out of contact with the needles operated thereby, substantially as described.
43. In a circular knitting machine having independent needles, the combination with a plurality of cam cylinders, each provided with a knitting cam for engaging a series of needles for producing plain knitting in the knitted web, of a fancy stitch cam coöperating with each knitting cam, and means for moving said fancy stitch cams into different positions, substantially as described. 120
44. In a circular knitting machine, the combination with a needle cylinder, of independently movable needles, cam mechanism for operating said needles to cause 125

them to knit, said needle cylinder and cam mechanism holding said needles from movement out of the plane of their reciprocation and means for automatically causing certain needles to drop their stitching and cease from knitting at a predetermined point and means for automatically causing said needles to again knit as and for the purpose specified.

45. In a circular knitting machine having independently movable needles, the combination with a plurality of cam cylinders, each provided with a knitting cam for engaging with a series of needles less than the entire number of needles for producing plain knitted fabric in the knitted web, of a fancy stitch cam coöperating with each knitting cam and engaging a less number of needles than its knitting cam, narrowing and widening mechanism coöperative with less than the entire number of cylinders and means for moving said fancy stitch cams

into and out of operative position, such means including provisions whereby the fancy stitch cams of the knitting mechanism 25 operative at such time may be maintained out of operation during the operation of the narrowing and widening mechanism, substantially as described.

46. In a circular knitting machine, the combination with special drop-stitch needles, of switches to control said needles, actuating members connected with said switches, an engaging member to coöperate with said actuating members, and means for shifting 35 the position of said engaging member with relation to the cylinder.

In testimony whereof I affix my signature, in the presence of two witnesses.
